(57) CLAIM

I claim the ornamental design for a shirt with an adornment, as shown and described.

DESCRIPTION

FIG. 1 is a front, side perspective view of a shirt with an adornment;

FIG. 2 is a front view of the shirt of FIG. 1;

FIG. 3 is a rear view of the shirt of FIG. 1;

FIG. 4 is a left side view of the shirt of FIG. 1;

FIG. 5 is a right side view of the shirt of FIG. 1;

FIG. 6 is a top view of the shirt of FIG. 1;

FIG. 7 is a bottom view of the shirt of FIG. 1; and,

FIG. 8 is an enlarged top, side perspective view of a portion of the shirt taken about line 8-8 of FIG. 1.

The ornamental design that is claimed is shown in solid lines in the drawings. The dashed lines shown in FIGS. 1-7 are included for the purpose of illustrating environmental elements only and form no part of the claimed design.
